UNITED STATES PATENT OFFICE.

CHARLES H. NORTON, OF WORCESTER, MASSACHUSETTS, ASSIGNOR TO NORTON GRINDING COMPANY, OF WORCESTER, MASSACHUSETTS, A CORPORATION OF MASSACHUSETTS.

STEADY-REST FOR USE ON GRINDING-MACHINES AND THE LIKE.

1,119,031.

Specification of Letters Patent.

Patented Dec. 1, 1914.

Original application filed June 6, 1913. Serial No. 772,055. Divided and this application filed July 22, 1914. Serial No. 852,388.

To all whom it may concern:

Be it known that I, CHARLES H. NORTON, a citizen of the United States, residing at Worcester, in the county of Worcester and 55 State of Massachusetts, have invented a new and useful Steady-Rest for Use on Grinding-Machines and the like, of which the following is a specification.

This is a division of my application for 10 patent on cylindrical grinding machine filed June 6, 1913, Serial No. 772,055, and relates to the steady-rest shown therein.

The principal objects of the invention are to provide a steady-rest of a simplified form 15 in which its contact with the work will be certain and positive and by which the friction of the moving parts will be reduced.

Reference is to be had to the accompanying drawings, in which—

20 Figure 1 is a plan of a steady rest constructed in accordance with this invention as applied to a grinding machine; and Fig. 2 is a side elevation thereof showing its support in section.

25 The invention is shown as applied to a grinding machine having a sliding table 5 provided with a support 6 thereon having a guiding surface or way 7 for the frame 8 of the steady-rest. This is provided with a

30 screw having a handle 9 for clamping it in any desired position along the guide or way 7. This steady-rest is shown as having an inclined body parallel with the surface of the guide or way on which it is carried

35 and on this are pivoted parallel links 10 extending upwardly from the main frame of the steady-rest. These links carry a rigid arch-shaped connecting member 11 thus affording a parallel motion. On this member

40 is pivoted a lever 13 which has surfaces 14 arranged to provide two rigid bearing points that can engage the work C and hold it in position. Carried by the member 11 is an inclined screw 15 for engaging a rear

45 projection 16 on this lever and adapted to swing the lever about its pivot so as to raise its work-engaging surfaces when the screw is forced in. A horizontal screw 17 is mounted on the steady-rest frame and en-

50 gages the member 11 to force it forward with a parallel motion when that screw is forced in. The end of the lever 13 extends upwardly to constitute a handle for opera-

tion by hand to force the lever back against the screw. This constitutes a simple and 55 convenient way of adjusting the bearing surfaces of the steady-rest either horizontally or up and down, or both as may be desired. The adjustment is always easily accomplished and is positive in every way. It 60 will be understood, of course, that the work is held between centers supported by the table but not herein shown.

Although I have illustrated and described only a single embodiment of the invention 65 and shown it as applied to a specific grinding machine, I am well aware of the fact that it is capable of general use and that modifications can be made in its construction without departing from the scope of the invention as expressed in the claims. Therefore, I do not wish to be limited in these respects, but

What I do claim is:—

1. In a steady-rest, the combination with 75 a support, of a parallel motion connection mounted thereon, means for adjusting said connection toward and from the work, and for positively holding it in adjusted positions, and means on said connection for engaging the work.

2. In a steady-rest, the combination with a support, of a parallel motion connection mounted thereon, means for adjusting said connection toward and from the work substantially horizontally, a lever pivoted on 85 said connection and having work-engaging surfaces projecting from it, and means on said connection for positively adjusting said lever about its pivot for the purpose of forcing said work-engaging surfaces upwardly 90 toward the work, and for positively holding it in adjusted positions.

3. In a steady-rest for a grinding machine, the combination of a support, a pair 95 of links pivoted to said support and arranged parallel with each other, a rigid member pivotally connected with the ends of said links, means for forcing said rigid member substantially horizontally toward the work, a lever pivoted on said rigid member for engaging the work, and means on said rigid member for engaging the lever and swinging it upwardly about its pivot.

4. In a steady-rest for a grinding machine, the combination of a support, a pair 105

- of pivoted links extending upwardly therefrom parallel with each other, a rigid member connected with the ends of said links at equal distances from their pivots on the support, a horizontal screw mounted on said support and engaging said rigid member to force it positively toward the work, a lever pivoted on the other end of the said rigid member and having surfaces for engaging the work and a projection on the opposite side of its pivot, and a screw on said rigid member for engaging said projection and positively swinging the lever upwardly toward the work.
15. In a steady-rest for a grinding machine, the combination of a support, a pair of links pivoted to said support and arranged parallel with each other, a rigid member pivotally connected with the ends of said links, means for forcing said rigid member substantially horizontally toward the work, and means on said rigid member for engaging the work.
20. In a steady-rest, the combination of a slanting support, a pair of links pivoted to

said support and arranged parallel with each other, one being higher than the other, a rigid member pivotally connected with the ends of said links, means for forcing said rigid member toward the work in a direction 30 parallel with said slanting support, and means on the rigid member for engaging the work.

7. In a steady-rest for a grinding machine, the combination of a support, a member movably mounted thereon, means for positively moving said member toward the work and holding it in adjusted positions, a work engaging member movably mounted on said support, and positive means for 40 forcing the work engaging member toward the work and holding it in adjusted positions.

In testimony whereof I have hereunto set my hand, in the presence of two subscribing 45 witnesses.

CHARLES H. NORTON.
